Frederick Freddly of Logan Township Pennsylvania
Setters Patent

The Schedule referred to in thea Setting Patent and making part
of the same containing a description in the words of the said
Frederick Freddly himself of his improvement being a mode
of lessening the friction on mill Spindles, and keeping them
perpendicular whilst running without being bushed entitled
"Freddly's improved mill Spindles".

Part Known that I Frederick Freddly of Logan Township
Centre County, State of Pennsylvania have invented an improve-
ment in the useful artz, being a mode of lessening the friction
on Mill Spindles, and keeping them perpendicular whilst
running, without the necessity of bushing, entitled "Freddly's
improved mill Spindles" which is described.

The Spindle may be made in the common form, or in any
other most convenient, except that there is a cylindrical
projection on it turned true, and below the bed stone, against
which the pulleys to be hereafter described turn.

There are three or more pulleys, or rollers about 18 inches
diameter turned true, and revolving on steel axles or cast
metal supports in suitable oil cups. These embrace the
Spindle closely at equal distances apart, and work against
the abovementioned projection turned on the Spindle.

Upon the bed stone is laid an iron plate, having a flange
turned upwards, about $3\frac{1}{4}$ of an inch, over this flange
or projection is placed a collar having a flange turning
downwards of a greater diameter than the one turned upwards
passing round the spindle and made fast to it and over the
flange of the plate, turning freely round but so close as to
prevent any grain from entering. Balls are placed in
a cavity in the bottom of the Spindles or judgements to pre-

500X

vent them meeting above. By this arrangement the pin
will be kept upright and will perfectly true. The collar & flange
prevent the grain falling through the opening in the bed,
which opening has heretofore been backed but is now to be
left open and the spindle covered by the flange mounted
in a collar. The invention here claimed and desired
to be secured by Letters Patent consists in the use of three
or more pulleys or rollers placed round the spindle to
keep it upright, serving also as a bush and preventing
wear and friction to the spindle, also in the use of the
collar and flange on the plate to prevent the grain pass-
ing thro' the eye of the bed.

For a further illustration of my invention I refer
to the model and drawing of the same deposited in the Patent
Office. In testimony whereof I have this day signed my
name this 19th day of February 1834.
